UNITED STATES PATENT OFFICE.

HUBERT SACKETT, OF PORTLAND, MAINE.

ORNAMENTAL DISPLAY SHELF FRAME.

Application filed July 17, 1923. Serial No. 652,020.

The object of my invention is to provide an adjustable or "elastic" ornamental frame, or border for the shelves of stores, made of cardboard or other suitable material upon which may be applied any suitable ornamentation and wording, preferably of such nature as to call attention to the specific articles on the shelves bordered by the frame. My device is adjustable to any size dealer's shelf and the construction which permits such result will hereinafter be fully described.

In the drawings forming part of this specification—

15 Fig. 1 illustrates in elevation an embodiment of the invention applied to two shelves.

Fig. 2 illustrates in elevation an embodiment of the invention applied to two shelves of twice the width of those illustrated in 20 Fig. 1.

Fig. 3 is a cross section on the line 3—3 Fig. 2.

Fig. 4 is a fragmental and sectional view, in elevation, of a corner of the frame.

25 Fig. 5 is a section on the line 5—5, Fig. 2, and

Fig. 6 is a plan view of that portion of the device illustrated in Fig. 5, partly broken away.

30 By reference to Fig. 1 it will be seen that the embodiment of the invention therein illustrated comprises side members *a*, corner squares *b*, centre squares *c*, *c'* top panels *e*, *e'*, bottom panels *f*, *f'* and the division strips *g*. The corner squares may be of the same height as the top and bottom panels, but for convenience in illustration I have shown them slightly larger.

Under each corner square *b* the adjacent 40 side member and top or bottom panel, as the case may be, overlap each other and each preferably extends to the edge of the corner member, as indicated in dotted lines. Under the centre square *c* top panel *e* abuts panel *e'* 45 at the median point *x* of the square, and likewise panels *f* and *f'* abut at the median line *x* of centre square *c'*. The division strips *g* are superposed upon two overlapping under strips *h* which are shown in Fig. 5 in their position when the frame is 50 adjusted to double the width shown in Fig. 1, as will be hereinafter explained.

The elements illustrated in Figure 1 of the drawings which are shown between the

horizontal panels, indicate goods on the shelves.

In the drawings I have illustrated no specific means for holding the elements of the device in relative position when assembled upon the faces of the shelves inasmuch as any of the well known metallic fasteners, in spring, prong or eyelet form may be employed for this purpose. And, of course, the elements may be permanently glued together when assembled and adjusted to a particular shelving.

Again referring to Fig. 1 of the drawings, it will be seen that to adjust the device for a shelf of greater width it is only necessary to move the corner squares with the side members the required distance, and this movement may continue until the outer edges of the top and bottom panels come into register with the inner edges of the corner squares. In this adjustment the overlapping under strips *h* (Fig. 5) for the division strips *g* are relatively moved in accordance with the length required, and the division strips themselves may again be equally spaced.

If desired, the division strips *g* may at their top and bottom margins be folded over upon the overlapping under strips, as illustrated in Figs. 5 and 6, also, the corner squares may at their top and bottom margins be folded over upon the adjacent top or bottom panel as the case may be and be glued or otherwise secured to overlapping under strips *j*, as illustrated in Fig. 3. If the adjustment provided for as described in the preceding paragraph is insufficient, the two top panels *e*, *e'* may be separated, and the two bottom panels *f*, *f'* correspondingly separated, this movement being possible until the inner edges of the panels come into register with the side edges of the centre squares.

The width of the device can be doubled by employing an additional set of top panels and an additional set of bottom panels, as illustrated in Fig. 2.

If increased height is desired, the necessary adjustment is secured by moving the top and bottom panels away from each other, and this movement can continue until the top and bottom edges of the side members *a* come into register with the edges of the corner squares. This will afford somewhat

- more than 50% increase in height of the frame. If 100% is required it is only necessary to employ two of the side members *a* for each side of the frame.
- 5 If less height is required than that provided for in the adjustment shown in Fig. 2, the top and bottom panels, with their appropriate corner members, can be moved toward each other and the ends of the side members projecting beyond the corner members can be cut off. If less width is required than that provided for in Fig. 2 the necessary portion of the margins of the top and bottom panels lying under the centre squares 10 *c* may be cut off and the panels again brought into abutment.
- 15 It will be understood that various modifications may be made in the form and device illustrated in the drawings, without

departing from the spirit of my invention 20 what I claim and desire to secure by Letters Patent being as follows:—

An ornamental shelf display frame, comprising a plurality of top panels arranged end to end and separately movable, 25 a plurality of bottom panels also arranged end to end and separately movable, centre squares normally superposed upon the top and bottom panels at their adjacent edges, side panels normally extending to the outer 30 edges of the top and bottom panels, and corner squares normally superposed upon the top and bottom panels and side members, said top and bottom panels and centre and corner squares being relatively adjustable. 35

In testimony whereof I have signed my name to this specification.

HUBERT SACKETT.
